(57) **CLAIM**

The ornamental design for a thaw plate, as shown and described.

DESCRIPTION

FIG. 1 is a first perspective view of a thaw plate showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is sectional view which is taken along line 9-9 in FIG. 4; and,

FIG. 10 is an enlarged view of the selected portion in FIG. 2.

The broken lines shown in the drawings depict portions of the thaw plate in which the design is embodied that form no part of the claimed design.
